(57) **CLAIM**

The ornamental design for an insect steamer spray tank assembly, as shown and described.

DESCRIPTION

FIG. 1 is a front view of an insect steamer spray tank assembly showing our new design, with the rear view being identical;

FIG. 2 is a right side view, with the left side view being identical; and,

FIG. 3 is a top view.

The broken lines throughout the drawings represent portions of the drawings, which form no part of the claimed design.
